US00D719654S

(12) **United States Design Patent**
Weitkamp

(10) **Patent No.:** **US D719,654 S**
(45) **Date of Patent:** **** Dec. 16, 2014**

(54) **MEDICAL INSTRUMENT**

(71) Applicant: **Sutter Medizintechnik GmbH**,
Freiburg (DE)

(72) Inventor: **Dirk Weitkamp**, Waldkirch (DE)

(73) Assignee: **Sutter Medizintechnik GmbH**,
Freiburg (DE)

(**) Term: **14 Years**

(21) Appl. No.: **29/437,193**

(22) Filed: **Nov. 14, 2012**

(30) **Foreign Application Priority Data**

Jul. 20, 2012 (WO) DM/078 867

(51) LOC (10) Cl. **24-02**

(52) U.S. Cl.

USPC **D24/143**

(57) **CLAIM**

The ornamental design for a medical instrument, as shown and described.

DESCRIPTION

FIG. 1 is a top, left perspective view of a medical instrument in accordance with my design, shown in an environment;

FIG. 2 is a top plan view thereof;

FIG. 3 is a bottom view thereof;

FIG. 4 is a rear elevational view thereof;

FIG. 5 is a front elevational view thereof;

FIG. 6 is a left side elevational view thereof;

FIG. 7 is a right side elevational view thereof;

FIG. 8 is a top, left perspective view of a medical instrument in accordance with my design, shown in an alternate environment;

FIG. 9 is a top plan view thereof;

FIG. 10 is a bottom view thereof;

FIG. 11 is a rear elevational view thereof;

FIG. 12 is a front elevational view thereof;

FIG. 13 is a left side elevational view thereof; and,

FIG. 14 is a right side elevational view thereof.

The broken lines shown form no part of the claimed design.

1 Claim, 12 Drawing Sheets
